UNITED STATES PATENT OFFICE.

MAX WEISS, OF NEW YORK, N. Y.

TOY DEVICE.

Application filed April 20, 1925. Serial No. 24,324.

To all whom it may concern:

Be it known that MAX WEISS, a citizen of the United States, residing at New York, in the county of Bronx and State of New York, has invented certain new and useful Improvements in Toy Devices, of which the following is a specification.

The invention relates to toy devices, more particularly to such as are actuated by a ball or like member travelling under the action of gravity. It has for its object to provide an inexpensive construction for a toy device of this character and wherein various members may be actuated in a predetermined timed relationship. The invention has for a further object to provide a construction which will admit of convenient interchange of the members actuated by the said rolling ball member.

The nature of the invention, however, will best be understood when described in connection with the accompanying drawings, in which—

Fig. 1 is a plan of the novel toy device as embodied by way of example in a musical apparatus.

Fig. 2 is a longitudinal vertical section therethru taken on the line 2—2, Fig. 1.

Fig. 3 is a side elevation thereof.

Figs. 4 and 5 are fragmentary detail views illustrating a modification and wherein different members which may be actuated from those indicated in the previous figures.

Referring to the drawings, 10 designates a suitable frame or board member in which is provided a longitudinally directed sinuous passageway or slotted guide 11 affording a tortuous path for the actuating member. The latter is in the nature of a metal ball, 40 marble or like spherical member 12 designed to roll along the slotted guide 11 from one end of the board to the other when the latter is given the necessary inclination. This may conveniently be effected by means of an end member 13 hingedly secured to one end of the board, as indicated, and whereby the said end is lifted and supported in elevated position to give the desired inclination to the board. This end member, moreover, 50 may be folded under when the toy is not in use thereby providing a substantially flat package for shipment.

Along the side edges of the board 10, furthermore, there is directed inwardly a series of parallel lateral slots or recesses 14 which are disposed with respect to the sinu-

ous guide-way 11 in manner such that the axis of each recess will lie substantially in the curved portion of said guide-way, the recesses 14 of opposite sides of the board thus alternating or being staggered relative to each other. Moreover, each of said recesses 14 is designed to accommodate a lever member 15 which, in the particular embodiment shown in Figs. 1 to 3, is in the nature of a striker member having a hammer 16 at the outer end for engagement with a sounding member or bar 17 which may be of metal or other suitable material. A said bar is located transversely of the longitudinal axis 65 of a corresponding recess; and may be mounted over spaced pins 18 upon either side of such recess and which are adapted to fit within registering perforations 19 of a bar. This will enable an interchange to 70 be readily accomplished so that different tunes of a simple character may be played thru the hammers striking the respective bars when the former are properly actuated, 75 and as will hereinafter be set forth.

To accomplish this oscillation of the lever or striker members 15, the inner end of each of said members is designed to project beneath the tortuous passage-way 11, preferably at the curved portions or bends thereof; and all are so arranged with respect thereto that contact will be had successively with the portion of the ball member 12 projecting thru the slotted guide as the ball 85 rolls over an end to cause thereby the other 90 end 16 to be raised or lowered in accordance with the particular manner of pivoting the levers.

A very simple means for mounting the levers consists in providing the under side 95 of the board 10 with lugs or ears 20 upon either side of the respective levers and from which are extended lateral spurs or trunnions 21 fitting in bearing openings 22 of the ears. In this manner, a very simple and inexpensive mounting is provided, as the ears 20 as well as the pins 18 may be cast or moulded as an integral part of the board 10 simultaneously with the provision of the tortuous guide-way 11 and recesses 14; while the lever member may readily be struck up from metal in a simple operation.

Of course, means may be carried directly by the lever ends 16 and the sounding bars 17 removed. For example, reference being had to Fig. 4 of the drawings, a small bell 25 is shown attached to the respective end of a

lever member which bell will be sounded when the lever is oscillated as hereinbefore set forth; or, in place of the bells a Figure 26, animal, clown, etc., Fig. 5, may be attached and be caused to simulate dancing thru oscillation of the lever.

I claim:—

1. A toy comprising an inclined member provided with a tortuous open guide-way to receive a ball designed to roll from top to bottom of said member and to project thru the guide-way, said member being provided with inwardly directed recesses along each of the side edges, levers oscillating within the said recesses, pivotally secured to said member and having an end disposed in the path of said ball for contact therewith, and means actuated by the opposite ends of the respective levers when the latter are oscillated by the ball.
2. A toy comprising a member provided with a tortuous open guide-way to receive a ball designed to roll from top to bottom of said member and to project thru the guide-way, said member being provided with inwardly directed recesses along each of the side edges, a support member hingedly secured to one end of the guide-way member to also give the same the desired degree of inclination, levers oscillating within the said recesses, pivotally secured to the underside of said member and having an end disposed in the path of said ball for contact therewith, and means actuated by the opposite ends of the respective levers when the latter are oscillated by the ball.
3. A toy comprising an inclined member provided with a tortuous open guide-way to receive a ball designed to roll from top to bottom of said member and to project thru

the guide-way, said member being provided with inwardly directed recesses along each of the side edges, levers oscillating within the said recesses, pivotally secured to said member and having an end in the path of said ball for contact therewith, and sounding bars mounted over the respective recesses and adapted to be struck by the respective ends of the levers.

4. A toy comprising an inclined member provided with a tortuous open guide-way to receive a ball designed to roll from top to bottom of said member and to project thru the guide-way, said member being provided with inwardly directed recesses along each of the side edges, levers oscillating within the said recesses, pivotally secured to said member and having an end disposed in the path of said ball for contact therewith, and interchangeable sounding bars mounted over the respective recesses and adapted to be struck by the respective ends of the levers.

5. A toy comprising an inclined member provided with a tortuous open guide-way to receive a ball designed to roll from top to bottom of said member and to project thru the guide-way, said member being provided with inwardly directed recesses along each of the side edges, ears provided on the underface of said member, levers pivotally mounted in said ears, extending into the respective recesses and having an end disposed in the path of said ball for contact therewith, and means actuated by the opposite ends of the respective levers when the latter are oscillated by the ball.

In testimony whereof I affix my signature.

MAX WEISS
